ELECTRON DISCHARGE DEVICE

Howard L. Steele, Jr., Bloomfield, N. J., assignor
to Westinghouse Electric Corporation, East
Pittsburgh, Pa., a corporation of Pennsylvania

Application February 12, 1948, Serial No. 7,767

10 Claims. (CL 250—27.5)

1

This invention relates to electron discharge devices which utilize a cavity resonator, or cavity resonators, and a velocity modulated beam of electrons therethrough, and for brevity will be referred to herein, as often occurs in the trade, as a resonator beam converter.

During the past several years development of these converters has resulted in production of three distinct types; namely, first, those wherein two or more resonators are employed and the beam makes a one way transit from a cathode to a collector; second, those known as reflex converters wherein the beam travels from the cathode toward a reflector and then is reversed in direction traveling over a part at least of the primary path; and third, those known as secondary emissive converters wherein a secondary emitting cathode replaces the reflector of the second type for returning secondary electrons to the single resonator. The present invention relates more particularly to the last mentioned type.

It is generally recognized in the trade that the secondary emissive converter is more efficient initially, but that the proportionately greater efficiency over the other types is maintained for only a portion of the effective tube life and that the change of efficiency is detrimental to use in the field.

Accordingly, an object of the present invention is to provide a secondary emissive converter wherein a high efficiency will be maintained for a longer period than heretofore, and specifically for the life span of the converter.

Another object of the invention is to maintain a copious yield of secondary emission throughout the life span of the converter.

Closely related to the foregoing object, the present invention has an objective of preventing contamination of the secondary emissive electrode.

Again, an object of the invention is to provide a structure embodying minimum modification of existing constructions of cavity resonator converters.

Corollary to the foregoing object is a further desideratum of maintaining conventional dimensions of present day converters in manufacture of the present invention.

Yet again, an object of the invention is to avoid obstructions in the beam path and at the same time provide a construction wherein the emissive surface of the secondary electron emitting electrode is not in the path of sight of the primary cathode.

2

Once again, an object of the invention is to suppress oscillation of electrons across the resonator gap and to suppress hysteresis.

Other objects of the invention will appear to those skilled in the art to which it appertains as the description proceeds both by direct recitation thereof and by implication from the context.

Referring to the accompanying drawing in which like numerals of reference indicate similar parts throughout the several views:

Figure 1 is a longitudinal sectional view of a cavity resonator converter constructed in accordance with my invention;

Figure 2 is a cross-sectional view looking toward the secondary emitter, taken on line II—II of Figure 1; and

Figure 3 is a sectional view looking away from the secondary emitter as upon line III—III of Figure 1.

20 In the specific embodiment of the invention illustrated in said drawing, there is shown a resonator beam converter fabricated as a body of revolution about an axis and providing a coaxial hollow resonant chamber, herein designated resonator 10.

The converter provides an evacuated enclosure within which is a primary cathode 11 transverse to and symmetrical upon said axis opposite one end of the resonator, and an opposed electrode

30 12 which functions as an anode with respect to cathode 11 and which is also transverse to and symmetrical upon the axis and at the opposite end of the resonator from said cathode. Said electrode 12 provides a middle portion 13 having a hollow 14 directed toward the cathode, and provides an annular substantially flat ring portion 15 radiating from the open end of said hollow. The surface 16 of said ring portion of said electrode which is directed toward the

35 cathode is emissive of secondary electrons and is here shown as having secondary emissive material thereon constituting the said surface 16 of the electrode. There are various materials known to be emissive of secondary electrons, of which silver magnesium is an example.

40 It is the secondary emission from said surface 16 of ring-portion 15 of said electrode 12 which goes back toward the cathode, gives up energy thereto at a desired frequency of oscillation in the resonator and produces the output energy by loss of energy of the secondary electrons to the resonator. In order to obtain return of secondary electrons to the resonator, proper polarities are applied by batteries or other 50 sources of potential (not shown) to the cathode,

secondary emitter, and resonator. It is necessary to have the secondary emitter more positive than the cathode, and usually, although not always necessary, to have the resonator more positive than the secondary emitter.

The converter furthermore provides a beam passageway partway through and coaxial to the resonator and comprised by the hollow interior of a cylinder 17 situated between the cathode and resonator and with a portion of the cylinder projecting into the resonator so that a constriction or gap 18 is provided between the end of said cylinder and the end of the resonator furthest from the cathode. According to the present invention, the end of the cylinder 17 nearest the cathode is partially closed by a disc 19, said disc having a central opening 20 therein. Similarly, the opposite end of the cylinder 17 is closed by a disc 21 having a central opening 22 therein. The end wall of the resonator through which cylinder 17 protrudes comprises a flexible diaphragm 23 sealed to said cylinder and sealed to the peripheral wall 24 of the resonator, which enables said cylinder to be adjusted with respect to the forward or fixed end 25 of the resonator, for tuning purposes. Between the cathode and said cylinder 17 is a focusing or electron restricting collar 26 which is shown frusto-conical in shape with the smaller end thereof toward the cathode. Contiguous to but electrically separate from the smaller end of the focusing collar is a focusing grid 27 thereacross and parallel to the cathode and also in close proximity thereto. The diameter of the smaller end opening of the focusing collar determines the maximum possible diameter of beam which can proceed therethrough toward the secondary emissive electrode. The focusing collar 26 and grid 27 are separately supported by suitable means such as the respective cylindrical metallic supports 26a and 27a which in turn are carried by the cathode insulator 11a.

The size of this opening as well as the size of the openings 20 and 22 in the discs at the ends of the cylinder 17, and the size of the hollow 14 in the secondary emitting electrode have definite relationship to each other, such that a straight line from any part of the area of the opening through the focusing shield directed forwardly through the openings of the cylinder 17 will intercept the secondary emitter electrode only within the hollow 14 thereof and not upon the portion 15 which has the secondary emitting face 16. Consequently, any electronic or other discharge from the cathode moving in straight lines therefrom to the secondary emitting electrode, cannot engage the secondary emitting surface. This restricted path from the cathode to said electrode will be referred to herein as line-of-sight.

Contamination of a secondary emitting surface from a primary cathode may result from particles from the cathode, and since such particles have a considerable mass in comparison to electrons those particles are not subject to deflection by electrostatic forces existing in a converter of the character described, and therefore will travel in a straight line and thus will be restricted to the line-of-sight path in travel to the hollow 14 in the present showing and will not strike the secondary emitting surface 16. Similarly, uncharged particles of matter such as vaporized material evolved from the cathode during operation thereof travel in straight lines and are not influenced by electrostatic conditions along the

path of travel, and therefore this source of contamination to which secondary emitting cathodes are susceptible, will not exist in the construction of the present invention since the secondary emitting material is removed from any straight line travel of matter of line-of-sight from the cathode.

On the other hand, electrons, being charged negative particles, may be deflected from the straight path, and that characteristic is made use of in the present invention. Between the fixed wall 25 of resonator 10 and the secondary emissive electrode 12, I provide an electron influencing member 28 here shown as a cylindrical collar secured to the said resonator wall 25 projecting toward the secondary emitting electrode 12 with its forward edge in proximity to said electrode near the perimeter thereof. The said member 28, by virtue of its support upon and attachment to the resonator 10, will have the same potential polarity as the resonator and is in any event more positive than the cathode. The electrostatic influence of this polarity upon the primary electrons from the cathode deflects the same away from the axis of the beam, or line-of-sight path thereof, as indicated by dotted line 29, and thus causes the electrons to impinge upon the secondary emitting surface 16. Since the secondary emissive surface will emit electrons in consequence of the impinging of the primary electrons upon the said surface, the secondary electrons are likewise influenced by the potential of said member 28 as they move toward the resonator and therefore tend to spread away from the axis or line-of-sight, as indicated by dotted lines 30. An enlarged opening 31 is provided in end wall 25 of the resonator adequate to pass the diverted or spread-out stream of secondary electrons. The secondary electrons pass through the large central opening 31 in the fixed end wall 25 of the resonator and phase relation is adjusted so they give up energy to the resonator in traversing the gap between said fixed wall and disc 21. This combination of the spreading of the primary beam electrons and of the secondary stream of electrons causes the secondary electrons to avoid the line-of-sight path and to be diverted to engage the solid portion of disc 21 in the resonator, which accordingly acts as a collector. Due to the spreading or umbrella action of the secondary electron beam above described, the secondary electrons will not be in a path through hole 22 of said disc 21 but all will engage the disc and be stopped thereby. The frequency at which the resonator operates depends upon what part of the radio frequency cycle the bunch of secondary electrons, represented by dotted lines 30, arrive in the gap 18. Without umbrella effect some of these electrons could pass completely through the gap and be available for another transit of the gap. These multiple transit electrons also influence the frequency of the cavity in similar manner. The number of multiple transits depends not only on the voltage of the secondary emitting element 12 but also upon the direction the voltage was made to approach the given voltage. The present invention eliminates the multiple transits and the accompanying hysteresis. Consequently, there is no oscillation of the secondary electrons back and forth with respect to the gap 18 between disc 21 and fixed wall 25 and thus no opportunity is presented for the electrons to introduce hysteresis or get out of phase and absorb any energy from the resonator.

If so desired, the hollow portion 13 of the secondary emissive electrode may have water or other fluid cooling associated therewith. As shown, the said portion 13 is secured in the mouth end of a cup-shaped coupling 32 which in turn is sealed to the end margin of a tube 33 which extends axially outward from the device and has appropriate vacuum sealing attachment to the fixed wall of the resonator by intervening structural parts, such as thimble 34, glass sleeve 35, metal joining sleeve 36, metal dome 37 and resonator head plate 38. The said tube 33 has a smaller tube 39 therein, the two tubes being utilized for fluid circulation which may be accomplished by using the smaller tube for entry of the fluid and the larger tube for discharge of the same to and from a chamber 40 within coupling 32 and next the end of portion 13 of the secondary emissive electrode. It will be understood that the converter is appropriately evacuated and sealed so that the electrons are discharged and remain in vacuum in their travel. Furthermore energy developed in the resonator may be conveyed therefrom in suitable manner as by an output loop 41 and its associated coaxial sealed output line 42.

The further structural detail may be mentioned that mechanical tuning is effected by varying gap 18 and to do this cylinder 17 is flanged at 43 at its end which protrudes from the resonator and the flange is sealed to a head plate 44 to which the cathode enclosure 45 is also sealed. Springs 46 tend to draw head plates 38 and 44 toward each other and adjustable screw props 47 between the plates hold them apart to desired extent.

It also may be added, that discs 19 and 21 in the ends of the beam passageway cylinder 17 act as grids for the primary beam electrons. A positive potential from a suitable source is applied to the resonator and discs 19, 21 and member 28, said potential being more positive than that which is applied to the cathode and preferably more positive than that which is applied to the electrode 12 in order that the direct current field of member 28 may be properly effective in controlling and deflecting the electron stream away from the axis or line-of-sight and also in order that the primary electrons passing forwardly through the accelerating field in the resonator may instigate secondary electrons from the secondary emissive face of electrode 12 that they may reach position in gap 18 of the resonator in phase with the field at a time when the field is decelerating to the secondary electrons. Potential gradient and distance of the secondary emitting surface 16 from the resonator gap 18 determines the positions attained by a primary electron and the secondary electrons instigated thereby during a phase change period of oscillation. The ideal desideratum is that a primary electron passing through and at a given reference position in the gap 18 of the resonator at phase condition of the oscillating field which is most accelerating to the electron, shall complete its transit to the secondary emitting surface 16 and instigate secondary electrons therefrom, which, starting at zero velocity, shall reach the said reference position of the primary electron in the resonator gap 18 when the oscillating field has reversed, which means 180° change, so the field will then be most decelerating to the secondary electrons. It is well known, but may be mentioned, that passage of the primary electrons through the radio frequency field in gap 18 of

the resonator induces bunching of the electrons which is complete by the time the electrons impinge upon the secondary emitting surface. The amount of secondary emission yield is proportional to the amount of primary electrons effective on the secondary emitting surface. Since the primary electrons are bunched, the charge density varying as it arrives at the secondary emissive surface, the secondary electrons will be exactly bunched in correspondence therewith.

The yield of the secondary emission will be greater than unity. Lateral deflection of the primary electrons causes them to impinge upon the secondary-emissive surface and that surface, being out of line-of-sight of the cathode is kept free of contamination from the cathode. Furthermore, deflection of the secondary electrons from the path of the primary electrons and catching of the secondary electrons on first passage into the resonator prevents hysteresis in the curve of secondary emitter voltage against frequency of the output.

I claim:

1. An electron discharge device comprising a resonator, means adjacent said resonator for producing and passing primary electrons through said resonator, an opposed electrode at the opposite side of the resonator from said electron producing means, said electrode having a non-emissive area in line-of-sight from said electron producing means and having a secondary emitting surface outside of said line-of-sight, and electron deflecting means between said resonator and surface for deflecting primary electrons from the non-emissive area to the emissive surface of said electrode in approach of said electrons toward the said electrode.

2. An electron discharge device comprising a resonator, means adjacent said resonator for producing and passing primary electrons through said resonator, an opposed electrode at the opposite side of the resonator from said electron producing means, said electrode having a non-emissive area in line-of-sight from said electron producing means and having a secondary emitting surface outside of said line-of-sight, and an annular electron deflecting member between said resonator and surface for deflecting primary electrons from the non-emissive area to the emissive surface of said electrode in approach of said electrons toward the said electrode, and for deflecting secondary electrons away from the path of the primary electrons.

3. An electron discharge device comprising a resonator having a beam passageway cylinder projecting thereinto and protruding therefrom at one end thereof, a cathode opposite the protruding end of said cylinder, a secondary emissive electrode at the opposite end of said resonator from said cathode, means in said cylinder for restricting line-of-sight between said cathode and electrode, said electrode having its secondary emissive surface entirely outside of said line-of-sight, and electron deflecting means between said resonator and surface for deflecting electrons in transit to or from and between said surface and resonator.

4. An electron discharge device comprising a resonator having a beam passageway cylinder projecting thereinto and protruding therefrom at one end thereof, a cathode opposite the protruding end of said cylinder, an opposed electrode at the opposite end of said resonator from said cathode, means in said cylinder for restricting line-of-sight between said cathode and elec-

trode, said electrode having a non-emissive area in line-of-sight from said cathode and having a secondary electron emitting surface outside of said line-of-sight, and electron deflecting means between said resonator and electrode for deflecting electrons in transit to and from and between said surface and resonator.

5. An electron discharge device comprising a resonator having a beam passageway cylinder projecting thereinto at one end thereof, said cylinder having a centrally apertured disc in the end thereof within the resonator, a cathode opposite the other end of said cylinder, a secondary emissive electrode at the opposite end of said resonator and cylinder from said cathode, said disc confining the line-of-sight between said cathode and electrode, and means proximate to said line-of-sight for deflecting secondary electrons away from said line-of-sight whereby said disc radially outside of its aperture intercepts secondary electrons from said electrode.

6. An electron discharge device comprising a resonator, a cathode at one end of said resonator, an electrode at the opposite end of said resonator, said electrode having a hollow central portion directed toward the resonator and on a common axis therewith and with said cathode, and said electrode having a surface transverse to said axis extending outward from said hollow portion and having its face toward the resonator emissive of secondary electrons, and electron influencing means offset laterally from said axis for diverting primary electrons from the cathode into engagement with said face.

7. An electron discharge device comprising a resonator, a cathode at one end of said resonator, an electrode at the opposite end of said resonator, said electrode having a non-emissive hollow central portion directed toward the resonator and on a common axis therewith and with said cathode and said hollow central portion intercepting the entire line-of-sight of the electrode from the cathode, and said electrode having a surface transverse to said axis extending outward from said hollow portion and having its face toward the resonator emissive of secondary electrons, and electron influencing means offset laterally from said axis for diverting primary electrons from the cathode into engagement with said face.

8. An electron discharge device comprising a resonator, a cathode at one end of said resonator, an electrode at the opposite end of said resonator, said electrode having a non-emissive hollow central portion directed toward the resonator and coaxial therewith and with the cathode, means between the cathode and electrode confining the line-of-sight between the cathode and electrode to the diametrical area of said hollow central portion of the electrode, said resonator having an opening in its wall toward the electrode of greater diameter than said hollow central portion of the electrode, said electrode having a surface emissive of secondary electrons, and electron influencing means offset from the line-of-sight between said electrode and cathode for diverting secondary electrons emitted from

said surface away from said line-of-sight for entry through said opening of greater diameter into said resonator.

9. An electron discharge device comprising a resonator, a cathode at one end of said resonator, an electrode at the opposite end of said resonator, said electrode having a non-emissive hollow central portion directed toward the resonator and coaxial therewith and with the cathode, and said electrode having a surface transverse to said axis extending outward from said hollow portion and having its face toward the resonator emissive of secondary electrons, means between the cathode and electrode confining the line-of-sight between the cathode and electrode to the diametrical area of said hollow central portion of the electrode, said resonator having an opening in its wall toward said electrode of greater diameter than said hollow central portion of the electrode, and electron influencing means offset from the line-of-sight between said electrode and cathode for diverting primary electrons from said cathode away from the line-of-sight and into engagement with the said secondary emissive surface of said electrode and for diverting secondary emitted electrons away from said line-of-sight and through said opening of the resonator.

10. An electron discharge device comprising a resonator, a cathode at one end of said resonator, an electrode at the opposite end of said resonator, said electrode having a non-emissive hollow central portion directed toward the resonator and coaxial therewith and with the cathode, and said electrode having a surface transverse to said axis extending outward from said hollow portion and having its face toward the resonator emissive of secondary electrons, a beam passageway cylinder between the cathode and said electrode and with an end thereof within the resonator and directed toward said electrode, a disc at said end of the cylinder, said disc having an opening therein confining line-of-sight from the cathode to a restricted area of the said electrode, and said electrode being emissive of secondary electrons at a part thereof outside of said restricted area, said resonator having an opening between said disc and electrode of greater size than said restricted area of the electrode, and electron deflecting means between said disc and electrode for deflecting primary electrons to the secondary emissive part of the said electrode and to deflect secondary electrons away from the opening of said disc, said secondary electrons being directed through the opening in said resonator and said disc functioning as a collector for the secondary electrons.
